UNITED STATES PATENT OFFICE.

JAMES DENNING, OF PITTSBURG, PENNSYLVANIA.

MANUFACTURE OF PRESSED GLASSWARE.

SPECIFICATION forming part of Letters Patent No. 230,534, dated July 27, 1880.

Application filed May 21, 1880. (No model.)

To all whom it may concern:

Be it known that I, JAMES DENNING, of Pittsburg, in the county of Allegheny and State of Pennsylvania, have invented certain new and useful Improvements in the Manufacture of Pressed Glassware; and I hereby declare the following to be a full, clear, and exact description of the same, reference being made to the accompanying drawings, in which—

10 Figure 1 is a transverse vertical section of a glass-press with my attachments. Fig. 2 is a front view of same.

In the manufacture of pressed glassware, such as goblets, tumblers, jellies, &c., the article is formed by forcing a plunger into a mold into which has been previously dropped a lump of molten glass. The entrance of the plunger then forces the soft glass into the interior shape figured by it and the mold; but 15 the operation being repeated at quick intervals, it has been found necessary to adopt some means for preventing the plunger from becoming too hot at its lower end, because if too hot it sticks to the glass and destroys the finish of the article in the withdrawal. The most 20 successful means hitherto found, and the one now in general use, is a blast of air directed upon the plunger; but it is directed indiscriminately upon the whole plunger. The result of this is, that the whole plunger is kept cool, and its upper part is held at a temperature insufficient for the proper working of the glass, which at that point is very thin and easily chilled, and in consequence the finished 25 article presents a wavy or "crizzled" appearance at its upper portion.

My invention, then, consists in so governing the air-blast by suitable means that it will strike only upon the lower part of the plunger, 30 keeping it cool, but preventing the current from impinging upon the upper part of the plunger, thus allowing it to store up sufficient heat to prevent crizzling.

It consists, further, in the specific means I 35 adopt to effect the above object, substantially as hereinafter fully described and claimed.

In the drawings, A designates a press-table of the ordinary form; B, the movable mold; C, the plunger fixed to the rod D; E F, the 40 lower and upper spring-plates, respectively; a, the spring-rods; b, the springs; c c, the

guide-posts or uprights, and G the blast-pipe. All these are as usual, and as such need no further description, being well understood by those skilled in glass-pressing.

With this construction it can be easily seen that the blast is unimpeded in all positions of the plunger. In its descent the blast strikes it under the spring-plate E, and when the spring-plate E reaches the mold then the blast 45 strikes the upper part of the plunger, as before stated.

I attach to the spring-plate E a holder, H, carrying a screen or deflector, I, as shown, whose lower edge extends a short distance below the spring-plate, and whose upper edge extends some distance above the top of the plunger, as shown in the drawings. The deflector I is made of sheet-iron, preferably, but may be of any form or material, and may be 50 located variably, according to the construction of the press. In some presses it may be found sufficient to have it above the spring-plate E, and not extending below it at all.

Arranged as in the drawings, it will be seen that when the plunger is in its highest position the blast can pass straight to the lower part of the plunger and cool it without touching the upper portion directly at all. As the plunger descends the screen I descends with 55 it, and when the plunger has gone a slight distance into the mold the screen I has reached the level of the top of the mold, thus cutting off the air entirely from the plunger. This allows the upper part of the plunger to retain 60 its proper heat, while the lower part is kept cool.

It is obvious that several different modes of reaching the same object might be adopted without departing from the scope of my invention.

I consider as embraced within my invention the following: an annular or segmental wall placed on the spring-plate, so as to shield the upper part of the plunger, made of any material capable of serving as a screen or deflector, either above the spring-plate alone or above and below it; or the nozzle might be attached to the spring-plate E or any of the movable parts of the press, and so adjusted as to be carried up and down with the spring-plate E while blowing across under it. Thus

the blast would strike the plunger below; but when the spring-plate E would reach the mold the blast would be shut off from the plunger entirely; or the blast-pipe might have a valve, 5 which could be arranged to shut during the descent of the plunger.

I therefore wish to be distinctly understood, as not limiting myself to any particular arrangement or construction, as my invention 10 embraces any means whereby the air-blast is so governed as to impinge only upon the lower part of the plunger.

What I do claim is—

1. The described improvement in the manufacture of pressed glassware, wherein a blast 15 of air is used to cool the plunger of a glass-press, consisting in confining, by suitable

means, the blast of air to the lower part of the plunger and directing it against the external surface thereof, substantially as described. 20

2. In glass-presses, a screen or deflector placed between the air-nozzle and the upper part of the plunger, substantially as described.

3. The combination of the mold B, plunger C, spring-plate E with the holder H, and 25 screen I, attached to the spring-plate E, and between it and the blast-pipe G, substantially as described.

In testimony whereof I have hereto set my hand.

JAMES DENNING.
